METHOD OF REGISTERING MULTICOLOR PRINTING PLATES

Robert R. Myers, Jr., Des Moines, Iowa

Application November 15, 1948, Serial No. 60,072

6 Claims. (Cl. 101—211)

1

The principal object of my invention is to provide a means whereby a plurality of different color printing plates for use on a rotary press may be easily, quickly and accurately registered with each other.

A further object of this invention is to provide an accurate means for registering a plurality of different color printing plates that may be accomplished by a workman not of special skill qualifications.

A still further object of my invention is to provide a means for quickly registering a plurality of colored printing plates that is economical and a time saver.

These and other objects will be appreciated by those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of one form of my means ready to be placed around the cylinder of a rotary printing press.

Fig. 2 is a perspective view of a number of my devices on a rotary press printing cylinder in different stages of progress to illustrate the manner in which they are used in the registering of multi-color printing plates.

Fig. 3 is an end view of a press illustrating the arrangement of the various color cylinder rollers to the compression cylinder.

Fig. 4 is a cross-sectional view of one form of my means.

Fig. 5 is a front view of my preferred means mounted on a printing cylinder.

Fig. 6 is a longitudinal sectional view of my preferred means ready to be placed on a printing cylinder and taken on line 6—6 of Fig. 5.

Fig. 7 is an inside perspective view of my preferred means.

Fig. 8 is an enlarged cross-view of a portion of my preferred means detachably mounted on a printing cylinder.

The most difficult phase in multi-color printing is the proper alignment and registering of the various color printing plates with each other so that the finished printed sheet will have the different color indicia at the proper places and there will be no objectionable overlap of colors nor characters. The usual procedure (when black is one of the colors) is to use the black impression as the basic one, and then move and adjust, progressively, the other color printing plates to register with the basic color and with each other. This is done mostly by trial and error, and it is obvious that much time, labor and materials are expended to even closely accomplish the proper registration of the plates. One reason is that the plates must be clamped securely on their cylinder presses, and to move the plate in any direc-

2

tion, all the clamps must be first loosened and then readjusted and tightened. Even then, however, there is no assurance that the plate is in proper position and only a test printing run can determine whether or not the plate has been properly placed. Indeed, it would be almost an accident if it were in absolute alignment with the basic color plate. The most that can be hoped for is that the plates will be reasonably in registration with each other after much work and time has been expended. I have overcome such problems by providing a means that will immediately give an impression guide for the plates to be adjusted; such guide being an actual impression of a printing from the basic color plate.

Referring to the drawings, I have used the numeral 10 to generally designate the impression cylinder of a rotary press having the usual color rollers 11, 12, 13 and 14. The cylinder 11 may be the black roller, the cylinder 12 the red roller, the cylinder 13 the blue roller and the cylinder 14 the yellow roller. Obviously, there may be other color rollers and not necessarily in the sequence above given. As is well known in such presses, when the finished printing takes place, a belt of paper extends around the cylinder 10 and between the cylinder 10 and the roller cylinders 11, 12, 13 and 14. The black cylinder roller 11 will carry the black printing plates, the cylinder roller 12 will carry the red printing plates, etc. As is well known in the trade, these plates on the color cylinders are detachably adjustably mounted by movable clamp means not shown in the drawings.

35 It is to such rotary color presses that I apply my invention and I will first describe the means as illustrated in Figs. 1, 2, and 4. The numeral 15 designates the base sheet pad member or plate of my means. This sheet member may be 40 made of any suitable material such as cardboard, certain types of plastic metal or like. It however must be of a thickness substantially that of the printing plate. It is necessary that it either be precured or flexible enough to wrap around a roller cylinder as shown in the drawings. Any suitable means may be used to fasten the sheet 15 onto and around the cylinder. As an illustration, it may have its back coated with a suitable adhesive, or the usual plate holding clamps 50 may be used, or it may be wrapped around the cylinder and secured with an adhesive tape 16. It must be held without slippage relative to the cylinder.

The front or outer face of the sheet pad 15 is 55 treated with a suitable sticky substance such as rubber glue 17 for yieldingly holding a transparent sheet 18 thereon. This sheet 18 may be of any suitable material such as cellophane, or transparent or translucent paper. Obviously, this sheet 18 or any part of it may be raised from or torn from the backing sheet pad 15.

The practical operation of my means is as follows:

With the roller cylinder 11 as the basic color, the black printing plates are secured thereon in the usual manner. No particular accuracy except page alignment is required as all the other plates will be registered to the black plate. Next, I secure a sheet pad 15 on the remaining color cylinders 12, 13 and 14. The press is then run and the black cylinder 11 will deposit the black indicia onto the impression cylinder 10. These cylinders are normally encased in a paper wrapping. Obviously, this black wet ink on the cylinder 10 will in turn be deposited on the outer surface of the transparent sheet 18 on each of the cylinders 12, 13 and 14. As soon as these sheets 18 are properly impressed with the black indicia 19 the press is stopped. The first step thereafter is to raise the transparent sheet 18 on the cylinder 12 at its area having the black indicia, and tear, cut or otherwise remove that portion of the sheet pad 15 below the raised area of its sheet 18, as shown in the drawings. This provides a place on the cylinder 12 for the red printing plate. Such plate 20 is then placed on the cylinder 12 in the place of that portion of the pad 15 that has been removed. By lowering the transparent sheet 17 with the black impression on it over the red printing plate, one can see at a glance where the red printing plate is located relative to the black print impression. It then is a simple matter to adjust and align the red printing plate so that it registers perfectly with the black impression 19 on the transparent sheet above it. Obviously, this easy aligning of the red printing plate will be accurate in all directions and angles, as one can easily see through the transparent sheet and observe the indicia on the red printing plate. Once the red printing plate is adjusted and fastened, the sheet 18 is torn off, or the entire sheet 15 may then be removed from the cylinder. In like manner, the remaining color cylinders are serviced and when completed, all the color printing plates will be accurately registering with each other. The same method is used in flat plate multi-color printing. In presses, therefore, the flat plates are not rotatably mounted as in rotary presses; but in like manner the flat basic color plate is secured in place, and a flat pad 15 with its transparent sheet 18 is mounted in place of each of the other flat color plates. The impression roller is then picking up ink from the basic color plate and depositing some of it onto each of the substitute pads, to form an offset or impression 19. The press is then stopped, and in the same manner as herebefore described, the sheet 18 of each of the pads is raised, and that portion of each of the pads thereunder removed, the respective flat printing plates substituted for those portions removed, the sheets lowered onto the plates, and the plates adjusted and secured accordingly.

From the foregoing, it will be readily appreciated that the various color printing plates need be only once adjusted and fastened to the press, and that thereafter the color printing will all be in proper and accurate registration. Furthermore, the first and only adjustment of each of the color printing plates will be easily and quickly accomplished.

In Figs. 5, 6, 7 and 8, I show my preferred means of using the transparent sheet 18. The principle is exactly the same as herebefore described. However, in these figures, I show the transparent sheet 18 secured along its leading end to a separate pad plate 21, with its main area

designed to extend over an independent pad plate 22. By this arrangement, after the basic color has been impressed on the sheet 18, the same is raised and the pad plate 22 completely removed from the press. After the printing plate has been properly adjusted and fastened under the sheet 18, then the pad plate 21 and sheet 18 are removed from the press as a unit. These members 21 and 22 may be of any suitable material. If desired, they may be pre-formed of metal, and used over and over again, with new transparent sheets. If they are made of metal or other hard substance, at least the member 22 should be covered with a resilient sheet 23 so that the transparent sheet will more readily take an ink impression. Also this preferred means provides an easy and quick method of detachably securing the pad plates to the printing cylinders. Most all such printing cylinders have spaced apart spirally extending grooves 24 for receiving mechanical clamps for holding the printing plates to the cylinder. This construction is well known in the art. Such grooves each have two oppositely extending channels 25 in its side walls, as shown in Fig. 8. I utilize these already present grooves to detachably fasten my pad plates. On the underside of my pad plates I mount a series of spring staples 26 fastened at their bases by solder or like. These staples have two oppositely extending hump portions 27 in its two prong portions, as shown in the drawings. The purpose of the two humps of each staple is to enter and yieldingly engage the two side channels of a groove, as shown in Fig. 8. By this arrangement the pad plates 21 and 22 will be capable of quick and easy placement on and removal from the printing cylinder.

Some changes may be made in the construction and arrangement of my method and means for registering multi-color printing plates without departing from the real spirit and purpose of my invention, and it is my intention to cover by my claims, any modified forms of structure or use of mechanical equivalents which may be reasonably included within their scope.

I claim:

1. The method of registering attachable and adjustable multi-color printing plates on rotary presses having a plurality of color cylinders and an impression cylinder common with said plurality of color cylinders, comprising; the placement of transparent sheet members onto some of the color cylinders of a rotary press prior to the placement of the color printing plates thereon, the placement of one color printing plate on at least one of the color cylinders not having a transparent sheet member, the running of the rotary press to impress the color indicia onto its impression cylinder and thence onto the transparent sheet members, the stopping of the press, the lifting of a portion of each of the transparent sheet members from their color cylinders and the placement of color printing plates on the color cylinders respectively, in such manner that they will properly register with the indicia on the transparent sheet member above them, the rigid fastening of said last mentioned plates to their respective cylinders, and lastly the removal of the transparent sheet members above said plates.

2. The method of registering attachable and adjustable multi-color printing plates on rotary printing presses having a plurality of color cylinders and an impression cylinder common with said plurality of color cylinders, comprising; the placement of a transparent sheet member onto

one of the color cylinders of a rotary press prior to the placement of the color printing plate thereon, the placement of a color printing plate on a second color cylinder of said press, the running of said press to impress the color indicia onto its impression cylinder and thence onto the transparent sheet member, the stopping of the rotary press, the lifting of that portion of the transparent sheet that has indicia impressed thereon from said first cylinder, the placement of a different color printing plate on said first color cylinder and under the raised portion of said transparent sheet, the registering of said second color printing plate with the indicia on the transparent sheet above it, the fastening of said second printing plate to said first color cylinder, and the removal of said transparent sheet from above said second printing plate.

3. The method of registering attachable and adjustable multi-color printing plates on rotary printing presses having a plurality of color cylinders and an impression cylinder common with said plurality of color cylinders, comprising; the placement of a sheet member having a thickness substantially that of a printing plate onto a color cylinder of a rotary press; said sheet member comprising a base sheet portion and a top transparent sheet portion, the placement of a color printing plate on a second color cylinder of the press, the running of the press to impress the color indicia onto its impression cylinder and thence onto the face of the transparent sheet portion, the stopping of the rotary press, the separating of that portion of the transparent sheet that has indicia impressed thereon from its base sheet portion, the removal of at least that portion of the base sheet portion below the indicia on the transparent sheet from the said first color cylinder, the placement of another color printing plate in the place of the base sheet portion removed, the registering of the last mentioned plate with the indicia on the transparent sheet above it, the rigid fastening of said last mentioned plate to its respective cylinder after it has been aligned with the indicia on the transparent sheet above it, and the removal of the transparent sheet from above said last mentioned printing plate.

4. The method of registering attachable and adjustable multi-color printing plates on a printing press having a plurality of color plate holders and an impression member common to all of said color plate holders, comprising; the securing of the basic color printing plate to one of the color plate holders of the printing press, the securing of a transparent sheet member to one of the other color plate holders of the press and in the place usually occupied by the secondary color printing plate, a plate member below said transparent sheet member having a thickness substantially that of said secondary color printing plate, the running of the press to indirectly transfer ink indicia from said basic color printing plate to said transparent sheet member, the stopping of the press, the removal of the plate member from below said transparent sheet member, the placement of the secondary color printing plate below said transparent sheet member and registering it with the impressed indicia thereon, the fastening of said last mentioned printing plate to the press and then the removal of said transparent sheet member from the printing press.

5. The method of registering attachable and

adjustable multi-color printing plates on a printing press having a plurality of color plate holders and an impression member common to all of said color plate holders, comprising; the securing of the basic color printing plate to one of the color plate holders of the printing press, the securing of a transparent sheet member to one of the other color plate holders of the press and in the place usually occupied by the secondary color printing plate, a plate member below said transparent sheet member having a thickness substantially that of said secondary color printing plate; said plate member having a resilient face adjacent said transparent sheet member, the running of the press to indirectly transfer ink indicia from said basic color printing plate to said transparent sheet member, the stopping of the press, the removal of the plate member from below said transparent sheet member, the placement of the secondary color printing plate below said transparent sheet member and registering it with the impressed indicia thereon, the fastening of said last mentioned printing plate to the press and then the removal of said transparent sheet member from the printing press.

6. The method of registering attachable and adjustable multicolor printing plates on a printing press having a plurality of color plate holders and an impression member common to all of said color plate holders, comprising; the securing of the basic color printing plate to one of the color plate holders of the printing press, the securing of a pad plate member to one of the other color plate holders of the printing press in the place of another color printing plate; said pad plate member having a thickness substantially that of the printing plate it has temporarily been substituted for and having a liftable transparent sheet portion on its top surface, the running of the press to indirectly transfer ink indicia from the basic color plate to the top surface of the transparent sheet of said pad plate, the stopping of the press, the lifting of at least that part of the transparent sheet having basic color indicia on it, the removal of at least a part of the pad plate portion below the raised portion of the transparent sheet, the placement of the secondary color printing plate below said transparent sheet and in the place originally occupied by that portion of the pad plate that has been removed, the lowering of the transparent sheet onto the secondary color printing plate, the adjustment and fastening to the press of the secondary color printing plate in alignment with the impressed indicia on its top surface, and the removal of said transparent sheet from above said secondary printing plate after it has been adjusted and fastened.
